UNITED STATES PATENT OFFICE.

JARED K. SMITH, OF KOLOA, HAWAII.

BED-PAN.

SPECIFICATION forming part of Letters Patent No. 460,288, dated September 29, 1891.

Application filed March 17, 1891. Serial No. 385,429. (No model.)

To all whom it may concern:

Be it known that I, JARED K. SMITH, residing at Koloa, on the Island of Kauai, Hawaiian Islands, a practicing physician, have 5 invented a new and useful Improvement in Bed-Pans, of which the following is a specification.

The bed-pans heretofore in use are stiff and unyielding, requiring to be manipulated 10 with great care to avoid causing pain, inconvenience, and sometimes injury to the patient and liable to spill their contents and soil the bed. It is also frequently necessary to lift 15 the whole body of a patient to get the pan in position so that the natural functions may be performed.

The method of constructing my improved bed-pan is illustrated in the following drawings, in which—

20 Figure 1 is a plan, and Fig. 2 is a vertical section at $x x$, Fig. 1. Fig. 3 is a perspective.

The object of my invention is to furnish for the use of invalids a bed-pan which is pliable, efficient, and easily adjusted under 25 the patient without pain, inconvenience, or danger of spilling its contents.

This bed-pan may be made of rubber, of leather, or of any material which can be made sufficiently elastic for the stiffer and 30 thicker parts and sufficiently pliable for the other parts; or it may be constructed of two or more materials.

I first take an oblong piece of flexible rubber, leather, or other substance to form the 35 bottom A of the pan, and which is sufficiently stiff to retain its general shape, while it will yield enough to pressure to fit the form of the patient's body. Sewed or otherwise fastened to the edges of the bottom, as by cementing, 40 like one side of a rubber water-bottle, is a cover B of soft pliable material, preferably rubber, which extends from each side and each end of the bottom toward the center, leaving there an oblong opening b of suitable size, as seen in Fig. 1. Across the lower 45 end and at the sides of this opening are attached to the pliable cover suitable upwardly-projecting walls or flanges C C, composed of material similar to the bottom and having 50 sufficient stiffness to cause them to stand perpendicularly upon the cover. A convenient height for these flanges is about two and

one-half inches. The side flanges should be rounded off, as shown in Fig. 2, and terminate within an inch or two of the upper end 55 of the opening. The lower end of the pan should be fitted with a neck and stopper D, as shown, for emptying the pan after washing. The upper end may, if desired, have a grommet-ring E to hang it up by, such a one 60 being shown in the drawings. If used, it should be flat and not cause any bunch in the pan; or the pan may be fitted with a ring at each upper corner, as shown in dotted lines in Fig. 1, to aid in the adjustment of 65 the pan when in use. The upper end of the pan, being composed only of the thickness of the bottom and the cover, is so thin that it may be slid under the body without raising the patient, this feature of my pan being frequently of great value, especially with very 70 feeble patients.

When in use, any suitable absorbing material G is placed inside of the pan on the bottom. I have used with satisfaction a towel 75 with the edges folded to make a raised edge along the front and sides of the bottom, and another towel or cloth may be folded and laid across the upper end of the pan which goes under the patient. The pan may be of 80 any desired size. I have found twelve inches long by ten inches wide a good size for an adult patient. After use the absorbing material should be removed and cleansed and the pan should be washed. 85

Having thus described my invention, what I claim as new, and desire to secure by Letters Patent, is—

1. A bed-pan constructed of flexible material, with a bottom, a cover having an opening, and flanges projecting up around the opening, substantially as described. 90

2. In a bed-pan, the combination of a stiff but somewhat flexible bottom with a soft pliable cover and the stiff but flexible projecting flanges, as and for the purposes described. 95

3. In a bed-pan, the combination of an elastic bottom, a soft pliable cover, and elastic front and sides with an absorbent material within the pan, as described. 100

4. A bed-pan constructed of flexible material, with a bottom, and a cover having an opening joined together to form an elastic body which is tapered at the upper end of the pan to the

thickness of the bottom and cover, thereby forming a thin yielding part beyond the opening, which may be passed under the body of the patient without lifting him or giving pain, 5 and flanges projecting up around said opening, substantially as specified.

In witness whereof I have hereunto signed

my name in the presence of two subscribing witnesses.

JARED K. SMITH.
